UNITED STATES PATENT OFFICE

154,210

DESIGN FOR A COMBINED EXTENSION KEY CHAIN AND WATCH

Nathaniel N. Okun, Far Rockaway, N. Y.

Application November 10, 1948, Serial No. 149,557

Term of patent 14 years

(Cl. D17—14)

To all whom it may concern:

Be it known that I, Nathaniel N. Okun, a citizen of the United States of America and a resident of Far Rockaway, in the county of Queens and State of New York, have invented a new, original, and ornamental Design for a Combined Extension Key Chain and Watch, of which the following is a specification, reference being had to the accompanying drawing, forming a part thereof, in which:

Figure 1 is a front elevational view of the combined extension key chain and watch showing my new design;

Figure 2 is a rear elevational view of the upper and main section thereof; and

Figure 3 is a side elevational view of the upper and main section thereof.

I claim:

The ornamental design for a combined extension key chain and watch, as shown.

NATHANIEL N. OKUN.
